ELECTRIC OSCILLATION CIRCUIT

Herbert Muth, Berlin, Germany, assignor to Tele-funkens Gesellschaft fur Drahtlose Telegraphie m. b. H., Berlin Germany, a corporation of Germany

Application April 19, 1930, Serial No. 445,599
In Germany May 24, 1929

13 Claims. (Cl. 250—40)

- This invention relates to radio frequency oscillation circuits and deals more specifically with oscillation circuits having a minimum frequency change with temperature variations.
- 5 Experience has shown that the natural frequency of electric oscillation circuits is greatly dependent upon the temperature, especially in the case of short waves. This will be readily understood since, to cause an appreciable frequency change, only extremely slight changes in form (deformations) as due to the thermal coefficient of expansion of the materials used in the presence of heat variations, are required. Now, in order that these changes in form may 10 be kept inside small limits, only materials possessing an extremely small coefficient of thermal expansion are used. In view of the fact that metal alloys having a small heat expansion coefficient (such as "Invar") are difficult to work into the desired form and when so worked often are subject to internal strains which affect their operativeness, recourse is had according to this invention to the use of insulators or non-conductors possessing a low temperature coefficient, such 15 as fused quartz, porcelain, or steatite which are covered externally with a metallic coat so that their surface is rendered conductive. Materials suitable for covering the non-conductor are copper and silver, because of their high conducting power. In 20 a preferred form the copper or silver coated non-conductor may be given an additional coating of gold or platinum in order to protect the conducting film from atmospheric effects. The said coatings may be applied by any desired method, say, 25 ceramically or electrolytically, or by both these processes. The requisite thickness of the film is governed by the frequencies to be used since it depends upon the depth of penetration of the alternating current into the material in question.
- 30 For high frequencies it need not be over a few hundredths of one millimeter thick.
- The manner in which the present invention is carried out will be readily apparent from the following description of a specific embodiment of 35 the same. In the drawing:
- Fig. 1 is a diagrammatic view of an oscillation circuit partly in section; and
- Fig. 2 is a cross-sectional view of the conductors used in the circuit of Fig. 1, the proportions being exaggerated for the sake of clarity.
- Referring in detail to the drawing the leads 40 13 and coil 10 comprise a non-conducting core 11 and a conducting coating 12 applied thereto as shown in Fig. 2. The leads 13 of the same structure as the coil 10 connect the coil to a condenser
14. The condenser 14 is made up of non-conducting plates 15 coated by the conducting material 16. Any suitable leads 16 may connect the oscillation circuit to the apparatus with which it is to be used. 5
- Having thus described my invention, I claim:
1. A radio frequency relay circuit the conductors inductance and condenser plates of which are composed of a hard, solid non-conducting material, a continuous layer of conducting material on said non-conducting material, and a continuous layer of chemically inactive conductive material on said last named layer of conducting material. 10
2. An oscillation circuit the capacitive and inductive elements of which are of a solid, non-conducting and hard base material, a continuous layer of copper superposed on said non-conducting base material, and a continuous layer of gold over said layer of copper. 15
3. An oscillation circuit including a tuning capacity, said capacity being composed of physically separated plates of non-conducting material, a layer of conducting material over said non-conducting material, and a layer of chemically inactive conducting material over said first named layer of conducting material. 20
4. An oscillation circuit including an inductance coil comprised of a base of non-conducting material possessing a relatively low temperature coefficient as compared with metals such as copper, and a continuous layer of conducting material superposed upon said base, in parallel relationship with a condenser comprised of two physically separated non-conducting plates of quartz 25 having superposed thereon highly conducting material such as copper or silver. 30
5. An oscillation circuit comprising an inductance having a single continuous core of solid non-conducting material, a continuous layer of 40 conducting material superposed on and fixed to said core, and a layer of chemically inactive conducting material over said first mentioned layer of conducting material.
6. An oscillation circuit comprising an inductance having a single continuous helical core of solid non-conducting material, a thin continuous layer of conducting material superposed on and fixed to said helical core, and a layer of chemically inactive conducting material over said 45 first mentioned layer of conducting material.
7. An oscillation circuit comprising an inductance having a single continuous helical core of solid non-conducting material, a condenser comprising two physically separated non-con- 50
- 55

ducting plates, a thin continuous layer of metal surrounding said helical core and said non-conducting plates, and conductive means for connecting in parallel relationship said inductance and said condenser.

8. An oscillation circuit comprising an inductance having a single continuous helical core of solid non-conducting material, a condenser comprising two physically separated non-conducting plates, a thin continuous layer of metal surrounding said helical core and said non-conducting plates, a plurality of rod-like members having a similar metallic coating as said inductance and said condenser for connecting in parallel relationship said inductance and said condenser.

9. An inductor comprising a conductor disposed in a coil of at least one turn, said conductor having a core of material having a low coefficient of thermal expansion fixed to a shell of conducting material having a high electrical conductivity and a relatively high coefficient of expansion.

10. An inductor comprising a conductor disposed in a coil of at least one turn, said conductor having a core of relatively low coefficient

of expansion and high rigidity, and a conducting shell fixed to said core and constrained thereby against expansion in the direction of the length of the core.

11. An inductor comprising a conductor disposed in a coil of at least one turn, said conductor having a core of nonconducting material having a low coefficient of thermal expansion fixed to a shell of conducting material having a high electrical conductivity and a relatively high coefficient of thermal expansion. 5

12. An inductance coil characterized by having a substantially constant inductance under varying temperatures, comprising at least one turn of a quartz rod plated with metal of high conductivity and having a high coefficient of thermal expansion. 15

13. The method of maintaining the inductance of a coiled conductor having a shell of material of a high coefficient of thermal expansion constant under varying temperatures, which comprises restricting the longitudinal expansion of said shell without interfering with the diametrical expansion of said shell. 20
